ATTORNEYS

UNITED STATES PATENT OFFICE.

GEORGE S. MORIN, OF MINNEAPOLIS, MINNESOTA.

ATTACHMENT FOR SHAMPOO BOARDS.

Application filed April 20, 1925. Serial No. 24,417.

This invention relates to an improved attachment for shampoo boards such as are commonly used in beauty parlors for shampooing, and more particularly relates to 5 such a device adapted to be fitted or detachably connected to one end of the board to provide a comfortable head rest for the patient.

An object of the invention is to provide 10 a head rest or cushion for a shampoo board comprising a flexible water-proof member having means thereon for detachably connecting it to the shampoo board.

A further and more specific object of the 15 invention is to provide such a device having a tubular or hollow bead provided thereon and adapted to be fitted over the edge of the throat of the shampoo board, thereby providing a head rest for the patient and 20 at the same time providing substantially a water-tight joint between the patient's neck and the board.

A further object is to provide a shampoo 25 board attachment which will require no special fitting for different boards but is adapted to be placed on the recessed edge of the board and fit the same regardless of any variation there may be in the form or shape 30 of the recess.

The particular object of the invention 35 therefore is to provide an improved water-proof head rest for shampoo boards.

Other objects of the invention will appear 40 from the following description and the accompanying drawings and will be pointed out in the annexed claims.

In the drawings there has been disclosed a 45 structure designed to carry out the various objects of the invention but it is to be understood that the invention is not confined to the exact features shown as various changes may be made within the scope of the claims which follow:

In the accompanying drawings forming 50 part of this specification,

Figure 1 is a vertical sectional view through a conventional form of shampoo board showing my invention applied thereto;

Figure 2 is a plan view of Figure 1;

Figure 3 is an end view of Figure 1;

Figure 4 is a perspective view of the attachment removed from the board;

Figure 5 is a detailed perspective view showing the preferred construction of the 55 tubular bead forming the head rest of the attachment; and

Figure 6 is a perspective view showing one of the clamps for securing the ends of the device to the shampoo board. 60

In the selected embodiment of the invention here shown, for purposes of disclosure, there is here illustrated a common form of shampoo board 7 having the usual discharge end 8 and the curved throat 9 adapted to receive the neck of the patient, as indicated in Figure 1. The board 7 is preferably adjustably mounted upon a standard 11 by means of an arcuate slot 12 having a bolt 13 mounted therein upon which a wing nut 14 is mounted for locking the board in its adjusted position. Upturned flanges 15 are provided on each side of the board downwardly to direct the water to the discharge end thereof, and the head end or throat 9 of the board is likewise provided with a flange 10 against which the neck of the patient is placed as shown in Figure 1. 75

Shampoo boards of ordinary construction, and such as the one shown in the accompanying drawing are usually not very comfortable for the patient to rest her head against, and it is therefore customary to place a folded towel in the throat 9 of the board to provide a cushion for the patient and also 80 to prevent water from getting into the patient's clothing when having her head shampooed. It is therefore desirable that means be provided for use in conjunction 85 with such a board to provide a comfortable head rest for the patient, and that such device be so constructed that it may readily and quickly be removed from the board for 90 cleaning and other purposes.

The novel head rest featured in this invention preferably consists of a flexible sheet of material or apron 16, such as rubber, having its upper marginal edge 17 folded upon itself to form a bead 18, as shown in Figure 4. In order to provide a bead of sufficient diameter to provide a suitable head rest, and also that it may be soft and flexible to add to the comfort of the patient, the marginal edge 17 is preferably folded over a hollow tube 19, as particularly shown 100 in Figure 5. This tube is preferably vul- 105

canized to the sheet or apron 16 so that it substantially becomes integral therewith, and the marginal edge 17 is also preferably vulcanized to the sheet 16 a short distance beneath the bead as indicated at 21 in Figure 5. By thus folding the sheet 16 over the hollow tube 19, which preferably is of rubber, the bead 18 will be of a suitable size to provide a convenient head rest and also means for preventing water from getting into the patient's clothing, when mounted upon the board as shown in Figures 1, 2 and 3. Also as a result of this novel construction, the bead 18 will be very soft and flexible so as to readily adapt itself to the curvature of the flange 10. In use and for sanitary reasons, a small hand towel may be placed over the attachment as is customary at present.

20 The means provided for detachably securing the attachment to the shampoo board preferably consists of a pair of suitable clamps 22 which are adapted to be fitted over each end of the bead 18 and also over 25 the upturned flange 16 at the head end of the board, as shown in Figures 1 and 2. A set screw 23 is provided in each clamp for securing it to the flange 10 to securely hold the attachment or head rest in position upon 30 the board (see Fig. 6).

The central portion of the device is preferably yieldably connected to the board by means of a tension spring 24 having one end 35 suitably secured to the marginal edge 17 of the apron 16 as shown in Figure 4. A hook 25 is secured to the opposite end of the spring to provide means for detachably securing the spring to the supporting means as shown in Figure 1. When the attachment 40 is mounted upon a shampoo board as shown in this figure, the spring 24 will function to yieldably hold the bead 18 against the upper edge of the flange 10 so that when the neck or head of the patient is placed 45 thereagainst, as indicated by the dotted lines in Figure 1, it will provide a comfortable head rest and at the same time will prevent water from escaping from the board around the neck of the patient, and thereby prevent water from getting into the patient's 50 clothing.

If desired the bead 18 may be constructed of a porous flexible material instead of being hollow as shown, and other methods 55 may also be employed for securing the attachment to the board without departing from the invention.

It will be noted from the foregoing that 60 my attachment does not have to be fitted to the board on which it is used. It is loosely supported in the clamps 22 and being of flexible material will readily conform to the curvature of the end of the board and the tension device 24 will serve to draw the attachment 65 snugly against the end of the

board and hold it there with a yielding pressure. My device, therefore, is capable of universal use, being readily applicable to any style or form of board.

I claim as my invention:

1. The combination with a shampoo board 70 having a recess adapted to receive the neck of the user, of a waterproof device adapted to form a guard for the clothing and shoulders of the user and having a yielding cushion-like portion against which the user's head is seated during the shampooing operation. 75

2. The combination with a shampoo board 80 having a seat formed therein to receive the neck of the user or patient, of a flexible waterproofing means adapted to protect the clothing of the user and having a tubular bead-like portion forming a seat against which the head of the user is placed and 85 provided with a watertight joint around the neck of the user.

3. The combination with a shampoo board 90 adapted to receive the neck of the patient or user, of means adapted to form a seat for the neck of the user and yield under pressure of the head thereon to provide a watertight joint around the neck of the user and a tension device for drawing said means to its seat upon said board. 95

4. The combination with a shampoo board 100 having a recess at one end thereof provided with a lip at the edge of said recess, of a flexible apron-like member mounted on said board and having a substantially tubular bead-like part supported over the edge of said board, the skirt of said apron depending below said bead-like portion, and said bead-like portion yielding under pressure 105 and forming a close-fitting seat for the neck and head of the user.

5. The combination with a shampoo board 110 adapted to receive the neck of the patient or user, of means adapted to form a seat for the neck of the user and yield under pressure of the head thereon and provide a watertight joint around the neck, and a coil spring device attached to said means for drawing it snugly to its seat on said board.

6. A device of the class described, comprising a flexible core, having secured thereabout a sheet of flexible material, to provide short and long skirt-like extensions, respectively adapted to engage a shampoo board and the neck of a person for the purposes 115 set forth.

7. The combination with a shampoo board 120 adapted to receive the neck of the patient or user and having clamps on the end portion thereof, of flexible means having a fold 125 fitted within said clamps and supported thereby against the end portion of the shampoo board, a flexible tubular member fitting within said fold and a tension device for drawing said fold against the edge of said 130

board and adapting it for boards of different sizes and shapes.

8. The combination with a shampoo board recessed to receive the neck of the patient or user, of means adapted to be seated on said board, and flexible to accommodate itself to boards with recesses of different shape, said

means being adapted to provide a water-tight joint around the neck of the user, and a device for holding said means in place ¹⁰ against the edge of said recess.

In witness whereof, I have hereunto set my hand this 16th day of April 1925.

GEORGE S. MORIN.
